UNITED STATES PATENT OFFICE

LEON H. CLARK AND WILLIAM S. SENGPIEL, OF PHILADELPHIA, PENNSYLVANIA, ASSIGNORS TO THE SIKES COMPANY, OF PHILADELPHIA, PENNSYLVANIA

CHAIR

Application filed June 21, 1928. Serial No. 287,173.

This invention relates to improvements in chairs and is particularly directed to an adjustment for the back of a chair.

In chairs, particularly those intended for a person at work at a desk, or those intended for service for a considerable length of time, it is frequently necessary to quickly adjust the back of the chair vertically to accommodate the particular needs of the occupant. It is also necessary under other conditions, as when one chair is used for a number of different people, to provide for this quick adjustment of the back in order to secure the maximum comfort for the occupant.

This invention is designed to provide a chair back adjustment which permits the instant adjustment of the chair by merely grasping the back and pulling it up or down, means being provided for temporarily retaining the chair back in its adjusted position against inadvertent motion.

Further objects are to provide a novel form of chair back adjustment which permits the rapidity of adjustment mentioned above, but which at the same time, secures the requisite strength without requiring any complicated or costly mechanism.

An embodiment of the invention is shown in the accompanying drawings in which:

Figure 1 is a rear view of the upper portion of a chair provided with the adjustable back;

Figure 2 is a view on the line 2—2 of Figure 1;

Figure 3 is a sectional view on the line 3—3 of Figure 1.

Referring to the drawings, it will be seen that a chair seat 1 has been indicated as provided with a bracket 2 attached thereto in any suitable manner, as for instance, by means of screws 3, although obviously other brackets and other modes of attachment could be employed without departing from the spirit of this invention.

At all events, the bracket is provided with a downwardly extending arm 4 provided with a flat face against which the flat face of a transverse bar 5 contacts. This transverse bar is preferably enlarged at its center, as indicated at 6, and at this enlarged portion it is provided with two rows of depressions 7.

These depressions are adapted to receive the heads of spring pressed plungers 8, such plungers being of the conventional design and of standard construction, as indicated in Figure 2, for instance.

The transverse bar or member 4 is provided with a bolt 9 which passes through an elongated vertical slot 10 formed in the arm 4 of the bracket, so as to permit limited vertical sliding motion of the bar 5 with reference to the arm 4 of the bracket. The bar 5 is curved in transverse cross section, as shown in Figure 3, and has rigidly bolted to its enlarged ends 11 a pair of downwardly extending side arms 12 of the chair back 13.

These side arms are preferably rearwardly curved at the portion indicated by the reference character 14 in Figure 1, and the back 13 is preferably shaped to fit the back of the occupant, particularly at the curved or small portion of the back, to thus secure the maximum comfort for the occupant.

It is apparent, therefore, that there is one position only for which maximum comfort is obtained for any given occupant. This position of the back is readily obtained by merely grasping the back and shoving it down or drawing it up as required, thus securing instant adjustment to the exact needs of the occupant.

The spring plungers 8, of course, may be replaced by other spring pressed fasteners, as desired, without departing from the spirit of the invention and although two rows of apertures or recesses 7 have been disclosed, it is obvious that one row only need be employed, if desired.

Further, it is preferable to provide the arm 5 with a pair of forwardly projecting ribs 15, as shown in Figure 3, to contact with the guide or arm 4, and to thus prevent lateral rocking of the back.

It will be seen that the construction of the chair is extremely simple and may be very cheaply produced.

Further, there are no complicated or delicate parts and there is no fastening, such as a bolt, wing nut, or hand wheel which need be operated to secure the adjustment of the

back. Instead, the back may be adjusted by merely grasping it and pushing it to the place desired.

Although the invention has been described in considerable detail, such description is intended as illustrative rather than limiting as the invention may be variously embodied and as the scope of such invention is to be determined as claimed.

10 We claim:

In a device of the class described, a seat member, an arm extending downwardly from the back portion of the seat member and having a longitudinal slot, a back including spaced side arms normally projecting below the seat, a transverse bar having its ends rigidly connected to the lower ends of the side arms, a transverse enlargement at the intermediate portion of the bar extending beyond one of the longitudinal edges of the bar and formed with a plurality of depressions arranged in spaced relation longitudinally of the enlargement, a bolt carried by the transverse bar at its intermediate portion and movable in the slot in the arm, spring pressed plungers carried by the arm and adapted to engage the depression for retaining the back in various adjusted positions with respect to the seat and spaced ribs 30 extending transversely of the bar upon opposite sides of the arm to form a guide for said arm.

In testimony that we claim the foregoing we have hereunto set our hands at Philadelphia, in the county of Philadelphia and State of Pennsylvania.

LEON H. CLARK.
WILLIAM S. SENGPIEL.
